UNITED STATES PATENT OFFICE.

CHESTER W. CHEATHAM, OF SEATTLE, WASHINGTON, ASSIGNOR OF ONE-HALF TO
J. N. NISSEN, OF SEATTLE, WASHINGTON.

MEASURING WEIR.

Application filed October 6, 1926. Serial No. 139,813.

My invention relates to devices of the nature of a weir, for use in measuring and controlling the discharge of water, and specifically to a device of this sort which will secure uniformity of discharge where the level of the water supply is variable.

My invention has been designed more particularly for use in irrigating ditches and its object to secure uniformity of discharge under varying levels of water in the supply ditch.

My invention resides in the combination of a weir board which is provided with radius rods extending to pivot supports extending upstream whereby it is capable of vertical movement, and a current impact board carried by the weir board at an angle to the flow of the discharged current, whereby the level of the discharge edge of the weir board will be maintained at a uniform depth below the supply head, thereby assuring a uniform rate of flow taken from a supply varying in level.

The accompanying drawings show the manner in which I have incorporated my invention in a device designed to measure and control the discharge from an irrigating ditch.

Figure 1 is a vertical section of the device taken on a plane extending lengthwise thereof, that is, parallel with the direction of flow of the discharged water.

Figure 2 is an end view taken from the discharge end, one end of the fixed weir board being broken away.

Figure 3 is a plan view showing, partly in section, the mounting of the movable weir board and the current impact or carrying board.

As a matter of convenience in manufacture and installation of my measuring device, it will be desirable in a large proportion of cases, to provide a box such that the complete device is self-contained. The self contained feature is, however, not a strictly essential feature. I have secured this self contained feature in the device as illustrated by providing a box-like casing comprising a bottom 1, side walls 10, a fixed weir board 11 and a closure for the water inlet end consisting of a fixed end section 12 and a vertically movable gate 13 operating in guide ways 14.

Such a box or casing as illustrated is installed with its supply end in communica-

tion with the ditch from which water is to be taken. The gate 13 permits complete cutting off of the flow whenever desired.

At the discharge end of the box I employ a fixed or permanent weir board 11. This extends above the box bottom a distance corresponding roughly with the range of rise and fall of the movable weir board. Stated in another way, it is necessary to provide a sump, of suitable depth, to receive the vertically movable weir board when dropped to its lowermost point.

The movable weir board 2 has at least its outer or downstream face shaped as a segment of a cylinder concentric with the pivot axis of the radius rods 20, which are secured to the movable weir board at vertically separated points as 22 at each side of the box and are pivoted at points 21 upstream from the board. These parts are so proportioned that the downstream curved face of the movable weir board makes as close a joint with the upstream face of the fixed weir board 11 as is feasible without producing a disturbing amount of friction.

The ends of the movable weir board 2 are designed to fit close to the side walls 10 of the box so as to minimize the leakage of water therebetween. Special means to secure this result may be employed. I have shown one such means, consisting of the two bars 3 and 30, the bar 3 being secured to the weir board 2 and the bar 30 to the side wall of the box. The abutting edges of these bars are cut to a circle which is concentric with the pivot axis 21 of the weir board. Surfaces of this character and position may be made to fit closely without great friction.

In conjunction with the foregoing parts I employ a current impact board 4 which is mounted upon or secured to the weir board 2 so as to present an inclined lower face to the current, whereby the discharging water will act thereon to raise it and support both it and the attached weir board at a level with respect to the level of the supply water, governed by the weight of the parts and the rate of flow of the water. The controlling factors may be adjusted to thereby insure a continuously uniform discharge head and therefore a uniform rate of discharge, even with a varying head in the supply source.

The current impact or supporting board 4

has side wings 40 which lie close alongside of the side walls of the box and extend upwardly to above the water level. A guide flange or bar 5 at each side of the box, extends upwardly from the weir board 2 and the impact board 4 has complementary guide members 43 and 44, interengaging to permit and secure vertical adjustment of the impact board relative to the weir board, thereby to vary the depth of the discharge opening. Any suitable manner of fixing these when adjusted may be employed. Means should also be provided whereby when these parts are adjusted they may be locked in position. For purposes of adjustment I provide the guide members 5, 43 and 44 with holes 45 for the reception of holding pins or bolts. To facilitate locking I employ a yoke 6, the ends thereof being bent to form an offset 60, which may be passed through the holes when the yoke body is swung upwardly but which cannot be removed when the yoke is down. A padlock 61 engaging the yoke and a staple 62 carried by the board 4, prevents moving of the yoke.

I have found that the lifting efficiency of the board 4 is increased if its discharge edge is extended somewhat beyond the top edge of the weir board 2 and particularly if this edge is slightly curved downwardly, as is shown at 41 in Figure 1. I have also found that the variation of angle of the impact face of the board 4, due to rise and fall thereof, will vary its lifting power, but that this may be compensated for by giving the upper sections of the board a curvature which is slightly convex to the water, as is shown at 42. This curvature will be located at such points and determined in amount by experiment and test.

Extending across the box well towards its discharge end but so as to not interfere with the dropping of the weir board 2 to its lower limit, is a partition 15. This forms a sump into which the lower edge of the weir board may sink and holds back any gravel and dirt which may wash into the box, so that it will not interfere with the fall of the weir board 2.

While I have described my invention as built into a box, the essential features may be installed otherwise than in a box. The use of a box will probably be found desirable for measuring devices of moderate and usual dimensions. To install such a device it is only necessary to dig a trench and embed the box therein.

When in use the elevation of the discharge edge of the weir board 2 is determined by the elevation of the source of supply, from which it follows that with an opening of constant area and under a constant head, a uniform rate of discharge will follow. As the device will be adjusted and locked in adjusted position by some one re-

presenting the canal organization, the delivery of the proper amount of water and no more is assured.

To facilitate securing a close fit between the outer face of the movable weir board 2 and the fixed weir board 11, I have provided a plate 7 secured to the upper edge of the weir board and adjustable towards and from the movable weir board 2. Plate 7 has transverse slots 70 which receive the holding screws 71. In this way it is possible to secure close positioning between the movable and fixed weir boards, without production of material friction and by projecting the upper edge of plate 7, wedging of floated material between the two is prevented. It is evident that the adjusting plate 7 should be mounted upon the weir board which is complementary to the one having the cylindrical face. Subject to this restriction, it may be mounted upon either the fixed or the movable weir board.

What I claim as my invention is:

1. In a water measuring and controlling device in combination, a fixed weir board, a vertically movable weir board positioned at the upstream face of the fixed board for vertical movements, a current impact board fixed above and relative to the movable weir board, and radius rods fixed in their relation to said movable board and extending in an upstream direction, a fixed pivot for the upstream ends of said rods, the movable weir board having a segment-cylindrical downstream face concentric with the pivot axis of the radius rods and positioned closely adjacent to the upstream face of the fixed weir board.

2. In a water measuring and controlling device in combination, a fixed weir board, a vertically movable weir board at the upstream face of the fixed board, and radius rods fixed in their relation to said movable board and extending in an upstream direction, a fixed pivot for the upstream ends of said rods, the movable weir board having a segment-cylindrical downstream face concentric with the pivot axis of the radius rods and positioned closely adjacent to the upstream face of the fixed weir board, and a current-impact board fixed in uniform relation to the movable weir board and upwardly spaced therefrom and adapted by the reaction of the water thereon to maintain the discharge opening at a constant hydraulic head under varying water supply levels.

3. In a water measuring and controlling device, a fixed weir board, a vertically movable weir board, radius rods secured in fixed relation to the movable weir board and pivoted upstream from the board to bring the fixed and movable weir boards in close juxtaposition of faces, a current-impact board fixed above and to move with the movable weir board in constant angular re-

lation thereto and to present a face angularly disposed to the current flow, and means for adjusting said current-impact board relative to the weir board to vary the depth 5 of the discharge opening beneath it.

4. In a water-flow controlling device, a vertically movable weir board, a current-impact board fixedly secured relative to the said weir board at an angle to the current 10 flow to thereby carry the weight of the weir board, said impact board having a zone towards its upper edge convexly curved to the current and at its lower edge another zone which is concavely curved towards the current. 15

5. In a water measuring device, a fixed weir board, a vertically movable weir board, means for automatically positioning the level of the movable weir board by the level of 20 source of water supply, and an adjustable member carried by one of the weir boards and adjustable towards and from the face of the other to control the volume of water discharge between them.

25 6. In a water measuring device, a fixed weir board, a vertically movable weir board, means controlling said movable weir board to swing about a pivot axis, the face of one of said boards which is presented toward the 30 other being a segment of a cylinder concentric with said pivot axis, and a plate carried by the other board, and adjustable toward and from the cylindrical surface of its complemental board.

35 7. In a water flow controlling device, a weir board, radius rods fixed relative to the weir board and pivoted to swing upon an upstream pivot, guides secured to move with

the weir board and extending upwardly from the discharge end of the weir board, a current-impact board having complemental guides engaging the beforementioned guides and means for adjusting said guide members to vary the relative position of the movable weir board and the impact board. 40 45

8. In a water flow controlling device, a weir board, means whereby said board is pivotally supported for a vertical swinging movement, a current impact plate associated and operably connected to move with the 50 weir board, the discharge edge of said impact board projecting beyond the weir board and being bent downwardly.

9. In a water flow controlling device, a weir board, means controlling the same for vertical movement in a circular arc having its center upstream, a current impact board carried by the weir board, and pairs of complemental arcuate members at each side of the weir board, to prevent leakage, one member of each pair being fixed relative to the movable weir board, and the other carried by said weir board. 55 60

10. In a water measuring device, a weir board, and means guiding the same for vertical movement, complemental fixed weir members, a current-impact board associated with and operably connected to the movable weir board to rise and fall therewith, and having an inclined bottom and enclosing 65 70 ends to thereby compel all the discharged water to pass under said impact board.

Signed at Seattle, Washington, this 15th day of Septemeber, 1926.
